UNITED STATES PATENT OFFICE.

MARY JOSEPHINE POST, OF HOBOKEN, NEW JERSEY.

GAME APPARATUS.

SPECIFICATION forming part of Letters Patent No. 550,803, dated December 3, 1895.

Application filed April 11, 1895. Serial No. 545,316. (No model.)

To all whom it may concern:

Be it known that I, MARY JOSEPHINE Post, a citizen of the United States of America, residing at Hoboken, in the county of 5 Hudson and State of New Jersey, have invented certain new and useful Improvements in Game Apparatus, of which the following is a specification, reference being had therein to the accompanying drawings.

10 This invention relates to certain improvements in games, and more particularly to that class of games employing spinners and marbles.

The object of the invention is to provide an 15 improved, simple, and yet interesting game employing spinners, marbles, and a suitable game-board, which can be easily understood and played and yet will develop considerable skill and accuracy.

20 The invention consists in certain novel features of construction and in combinations and arrangements of parts, more fully and particularly described and set forth herein-after.

25 Referring to the drawings, Figure 1 is a perspective view of the game complete. Fig. 2 is a longitudinal section of the marble-projector. Fig. 3 is a detail view of the meeting ends of two sides or walls, showing the socket 30 to receive the tenon of a projector. Figs. 4 and 5 are detail views.

In the drawings, *a* is the game-board, divided into four equal portions or squares 1 2 3 4, if the board be square, each of a different color from the others and separated from the others by dividing lines 5 6. A circle 7 is located at the center of the board, distinguished from the squares by color or otherwise. Each square has a circle 8 indicated 40 thereon near its outer corner.

The board is surrounded by an elevated edge or wall *b*, divided into four sections 1' 2' 3' 4', colored similarly to the four portions of the board. Each section extends along one 45 side of the board and a short distance on another side at the corner occupied by the portion of the board of the same color as the section.

50 *c* are marble or ball projectors arranged at the four corners of the edge and all pointed toward the center ring of the board. Each

projector is composed of a downwardly-inclined tube formed to rest on the edge wall with a tenon *c* to enter the socket in the edge wall. The upper end of the tube has a groove 55 *c*² to hold the marble until pushed into the tube *s*, so that gravity will carry the marble through the tube and across the table.

d are grooves in the top surface of the edge to receive the marbles *e* to be discharged by 60 the projectors across the board.

f are spinners, each of the four portions or colors being represented by spinners of like color, and a like number of spinners are provided by each color. 65

g are flags, one or more flags being provided for each color, and each section of the wall has an opening to removably receive its flag. Usually each color is provided with four flags, for the purpose hereinafter stated. 70

Briefly stated and without going into detail, the way of playing the same is substantially as follows, viz: Four persons play the game, and each person takes a side color and plants his flag thereon. The person playing the first 75 then twirls a spinner on the center circle and each discharges a marble from his projector at the twirling spinner by pushing a marble from groove *c*² into the tube, and the spinner belongs to the player whose marble strikes it. 80

The persons around the board play in succession, and suitable simple rules can be established to cover all points arising, the object of the game being to secure all the spinners of the opposing player, and when a player 85 loses all his spinners his flag is removed and the flag of the person receiving the spinners is substituted, and such person also occupies the square of the losing player.

If the marble before mentioned fails to hit 90 the twirling spinner, it belongs to the player into whose square it rolls and stops.

If a spinner in its movements passes into one of the corner rings on the board, the player diagonally opposite can shoot at the game and 95 take the spinner if he hits it.

The game can be made interesting and develop great skill under proper rules.

It is evident that I do not limit myself to any particular shapes, dimensions, or colors. 100

What I claim is—

1. A game apparatus comprising the board

divided into equal portions each distinguished from the others, the surrounding wall divided into like portions, the projectors, the flags, spinners, and balls, substantially as described.

5. 2. The game apparatus comprising the board divided into four equal and differently colored portions, the surrounding wall formed to receive the marbles, the walls divided as

shown and the corner projectors substantially as described.

In testimony whereof I affix my signature in presence of two witnesses.

MARY JOSEPHINE POST.
